SKIBINDING DEVICE

Johan Henrik L'Abée-Lünd, Slemdal, near Oslo,
Norway, assignor to L'Abée-Lund Aktieselskap,
Oslo, Norway

Application December 5, 1933, Serial No. 701,063
In Norway July 14, 1933

4 Claims. (Cl. 208—184)

My invention relates to ski bindings and more especially to devices serving as holder for the toe part of the skiing foot. These devices usually comprise two lugs projecting upwards from the 5 footplates which are adjustably fastened to the ski by way of screws, passing through transverse slots in the said footplates.

The object of my invention is to improve the means for adjustably holding these lug irons to the 10 ski, and for this purpose my invention consists in the combination with the said toe lugs of a plate, covering the said footplates and adapted to hold the same in any desired position, by means of friction or by means of tooth- 15 engagement. A further purpose is to improve these devices so that they may be manufactured in a cheap way and allow of a very accurate adjustment.

My invention is illustrated in the accompanying drawing, showing some forms of carrying out the same.

Fig. 1 is a ground plan view and

Fig. 2 a longitudinal vertical section on the line II—II Fig. 1 of one form of my invention.

Fig. 3 is a ground plan view of another form of my invention.

Fig. 4 is a perspective view of toe holding lug irons, illustrating some details.

Fig. 5 is a perspective view of a modification. 30 Figure 6 is a cross sectional view of a curved plate *e* prior to its securing to a ski.

Figure 7 is a similar cross sectional view of a flat plate *e'* prior to its securing to a ski.

Figure 8 is a cross sectional view of a curved 35 plate *n* which is used in the modification shown in Figure 3, and

Figure 9 is a cross sectional view of a flat plate *n'* such as can be used with the modification shown in Figure 3.

40 In the form of carrying out the invention shown in Figs. 1 and 2 (see also Fig. 4) there is found in the foot-plate *a* of the lug an abutment *b*. This abutment is—as will be seen—from Fig. 4—formed by a pressing operation in dies, where-

45 by the material in the footplate is cut near the front and back edge and the strip outside the cutting line pressed up so as to form a rib or abutment. Between these ribs oblong apertures *c* are provided in the footplate, through which the screws *d* pass. The lug irons may in this 50 way be adjusted sideways and may also be angularly regulated. A plate *e* serves to secure the lug irons. The front and rear edge *f* of this plate both have the form of a line composed of two curves, which touch the abutments as shown

in Fig. 1. The plate *e* has, as shown in Fig. 2, an arched form so that, when the screws are tightened, the edges of the plate will be pressed against the abutments of the footplates of the lug irons, thereby securing the adjusted position of the same by friction. As will be seen, the whole device may be formed of sheet material by pressing and cutting operations.

5 The device shown in Fig. 3 differs from the one just described only therein that the abutments *p* and the corresponding edges of the plate *n* are provided with teeth *o*. The plate may, as in the form first described, be bent or arched so that the teeth will come out of engagement with each other, when the screws are loosened, or the plate 10 may be plane, and it will then, when the screws are loosened, have to be lifted to bring the teeth 15 out of engagement.

The plate *n* may in this latter case be provided with teeth arcs also on the side edges, along the 20 dotted lines indicated. These teeth on the side edges may be so cut that, when the plate is turned 90 degrees, the engagement with the teeth on the lug irons will bring these in intermediate positions of those obtained when the plate is in the 25 other position.

I claim:

1. In a skibinding device for holding the toe part of the skiing boot, the combination with footplates adapted to be adjustably secured to the ski, of a plate held on top of the same by way of screws, passing through oblong apertures in the aforesaid footplates, said footplates having at the front and rear edges upwardly projecting ribs, adapted as abutments for said plate. 30

2. In a skibinding device for holding the toe part of the skiing boot, the combination with footplates adapted to be adjustably secured to the ski, of a plate held on top of the same by way of screws, passing through oblong apertures in the aforesaid footplates, said plate having its front and rear edge formed on an arc line and said footplate having at the front and rear edges straight ribs, serving as longitudinal abutments for the arc shaped edges of the said plate. 40

3. In a skibinding device for holding the toe part of the skiing boot, the combination with footplates adapted to be adjustably secured to the ski, of a plate held on top of the same by way of screws, passing through oblong apertures in the aforesaid footplates, said footplates having at the front and rear edges upwardly projecting ribs, adapted as abutments for said plate, the latter being bent or arched so that by tightening the screws, sufficient friction will be created between 50

the abutment ribs and the plate edges to secure the position of the lug irons.

4. In a skibinding device for holding the toe part of the skiing boot, the combination with foot-plates adapted to be adjustably secured to the ski, of a plate held on top of the same by way of screws, passing through oblong apertures in the aforesaid

footplates, said footplates having at the front and rear edges upwardly projecting ribs, adapted as abutments for said plate, the edges of the plate and of the abutment ribs being provided with teeth, the engagement between which locks the lug irons in desired positions.

JOHAN HENRIK L'ABÉE-LUND.
